(57) **CLAIM**

I claim the ornamental design for a scent cartridge holder, as shown and described.

DESCRIPTION

FIG. 1 is a top, front, left side perspective view of a first embodiment of the scent cartridge holder of the new design. FIG. 2 is a front elevation view of the scent cartridge holder of FIG. 1.

FIG. 3 is a rear elevation view thereof.

FIG. 4 is a right side elevation view thereof, the left side elevation view being a mirror image of the right side elevation view.

FIG. 5 is a bottom plan view thereof, the top plan view being a mirror image of the bottom plan view.

FIG. 6 is a top, front, left side perspective view of a second embodiment of the scent cartridge holder of the new design. FIG. 7 is a front elevation view of the scent cartridge holder of FIG. 6.

FIG. 8 is a rear elevation view thereof.

FIG. 9 is a right side elevation view thereof, the left side elevation view being a mirror image of the right side view elevation view.

FIG. 10 is a bottom plan view thereof, the top plan view being a mirror image of the bottom plan view.

FIG. 11 is a top, front, left side perspective view of a third embodiment of the scent cartridge holder of the new design. FIG. 12 is a front elevation view of the scent cartridge holder of FIG. 11.

FIG. 13 is a rear elevation view thereof.

FIG. 14 is a right side elevation view thereof, the left side elevation view being a mirror image of the right side elevation view; and,

FIG. 15 is a bottom plan view thereof, the top plan view being a mirror image of the bottom plan view.

The broken line showing of features of the scent cartridge holder forms no part of the claimed design.
